UNITED STATES PATENT OFFICE

2,465,934

REFRIGERATED DISPLAY CASE

Ernest E. Sanders, Detroit, Mich.

Application June 28, 1945, Serial No. 602,083

6 Claims. (Cl. 62—89.5)

1

The present invention relates to refrigerated display cases and more specifically to cases of the type in which access to the products on display is had from the upper side of the display container.

Among the objects of the invention is a more efficient arrangement of the several elements of the construction so as to provide for better cooling of the contents.

Another object is a case in which the several elements are so arranged as to provide for more efficient operation and maintenance of the refrigerating unit.

Still other objects and advantages will be apparent to those skilled in the art upon reference to the following description and the accompanying drawings in which

Figure 1 is a perspective view of the case.

Figure 2 is a sectional view of the case on line 2—2 of Figure 3.

Figure 3 is a sectional view on line 3—3 of Figure 2.

Figure 4 is a sectional view on line 4—4 of Figure 3.

The case is shown in Figure 1 to be of more or less conventional appearance, having an upper display compartment 10A or receptacle accessible through doors 12 and provided with a glass front 13.

The display compartment will be heat insulated at its ends and bottom and in front and at the rear as indicated at 14.

As shown, the case above the level of doors 12, that is, above the highest part of the display compartment 10A, is provided with an upward extension, insulated on top and in its four walls and containing a chamber 20, which is narrow from front to back and extends from one end of the case to a point short of the other end, leaving an uninsulated chamber 21 at this other end.

The brine tank or container for the case is indicated in Figures 2, 3 and 4 as consisting of a main or header portion 25 occupying the chamber 20 and having a lower forwardly extending portion 25A overhanging the rear part of compartment 10A, and having leg portions 25B extending down and back and end walls of compartments 10 and 10A. This header 25B may also connect with hollow partitions 25C dividing the compartment 10A into plurality of smaller compartments as in my prior Patent No. 2,204,919, issued June 18, 1940. However, these partitions or dividers may be omitted if desired.

Within the extension chamber 20 in this por-

2

tion of the brine tank is located the evaporator 30, this being preferably of the plate type, that is, a continuous coil is produced by forming a sinuous channel in a metal plate and welding over this a flat plate.

The compressor unit is located in compartment 21 and being elevated may be easily accessible. In this position, too, more efficient dissipation of the heat generated by the unit may be had.

10 In addition to the legs 25B and the dividers 25C, a small longitudinally extending brine containing plate 35 is arranged in spaced relation to the window 13 and between these is located a small longitudinal shelf 36. This plate 35 will of course connect with the header 25 through the legs and dividers.

It is also proposed to provide a narrow counter 40 above the window 13 extending backwardly over the shelf 36 and its contents. These latter, 20 however, will be plainly visible through the window. Further, suitable drain means 45 will be provided leading from the lowest point of the compartment 10A.

The arrangement of the several elements in the 25 manner indicated provides for the maintenance of the coldest brine well above the space to be refrigerated and, therefore, greatly increases the rapidity of the circulation of the brine.

Further, with the large area of the header 30 exposed over the rear of the compartment 10A, there is an increased circulation of the air in the compartment, the air immediately adjacent the header and toward the rear of the compartment being rapidly cooled, and to a much lower temperature, immediately falls in the rear portion and produces a corresponding upflow in the front portion.

What I claim is:

1. A refrigerated display case consisting of a 40 receptacle having heat insulated side and bottom walls, and having access thereto through the upper wall, an upward extension at the rear of said receptacle, said extension being heat insulated and providing a chamber open to said receptacle, a brine tank in said extension, said tank being provided with hollow plate legs extending down the sides and back and within said receptacle and having a portion extending forwardly into said receptacle and overhanging a 45 portion thereof, a refrigerant evaporator within that portion of said tank that is located in said extension and a liquefying unit connected to said evaporator.
2. In a refrigerated display case of the type 50 wherein access to the contained space is through

the upper wall, a brine tank located above the level of said space and having a portion overhanging part of said space, hollow plate-like legs connected to said tank and lining at least a portion of the said side walls of said space, a refrigerating coil in said tank, and a liquefying unit connected to said coils.

3. In a refrigerated display case of the type wherein access to the contained space is through the upper wall, a brine tank located above the 10 level of said space and having a portion overhanging part of said space, hollow plate-like legs connected to said tank and lining at least a portion of the side walls of said space, a refrigerating coil in said tank, and a liquefying unit connected to said coils, said unit being also located above the level of said space.

4. In a refrigerated display case of the type wherein access to the interior food compartment is through an opening in the upper wall, a brine tank located above the level of said opening and having a portion overhanging part of the interior food compartment, a plurality of hollow plate-like legs connected to said tank and lining at least a portion of the side walls of the interior of said case, a plate-like hollow header extending downwardly at the rear of said space and connected to the said legs and tank, a refrigerating plate in said tank, and a liquefying unit operatively connected to said plate.

5. In a refrigerated display case of the type wherein access to the interior food compartment is through an opening in the upper wall, a brine tank located above the level of said opening and having a portion overhanging part of the interior food compartment, a plurality of hollow-plate-

5

like legs connected to said tank and lining at least a portion of the side walls of the interior of said case, a plate-like hollow header extending downwardly at the rear of said space and connected to the said legs and tank, some of said legs serving to divide said interior into a plurality of small compartments, a refrigerating plate in said tank, and a liquefying unit operatively connected to said plate.

15

6. In a refrigerated display case of the type wherein access to the interior food compartment is through an opening in the upper wall, a brine tank located above the level of said opening and having a portion overhanging part of the interior food compartment, a plurality of hollow plate-like legs connected to said tank and lining at least a portion of the side walls of the interior of said case, a plate-like hollow header extending downwardly at the rear of said space and connected to the said legs and tank, a longitudinally extending hollow plate arranged adjacent to but spaced from the front wall of the said case therewithin and connected to said legs, a refrigerating plate in said tank, and a liquefying unit operatively connected to said plate.
